DESIGN FOR A DISPLAY STAND

Thomas Beyrle, Los Angeles, Calif.

Application January 4, 1938, Serial No. 74,075

Term of patent 7 years

To all whom it may concern:

Be it known that I, Thomas Beyrle, a citizen of the United States, residing at Los Angeles, in the county of Los Angeles and State of California, have invented a new, original, and ornamental Design for a Display Stand, of which the following is a specification, reference being had to the accompanying drawing, forming part thereof.

Fig. 1 is a front elevational view of the display stand, showing my design;

Fig. 2 is a side elevational view;

Fig. 3 is a top plan view; and

Fig. 4 is a perspective view thereof, taken from the front and side;

Fig. 5 is an enlarged sectional view, taken as indicated by the line 5—5 of Fig. 1;

Fig. 6 is an enlarged sectional view, taken as indicated by the line 6—6 of Fig. 1; and

Fig. 7 is an enlarged sectional view taken as indicated by the line 7—7 of Fig. 1.

I claim:

The ornamental design for a display stand as shown.

THOMAS BEYRLE.
